APPARATUS FOR RAILWAY TRAIN
COMMUNICATION SYSTEMS

Willard P. Place, Penn Township, Allegheny County, Pa., assignor to The Union Switch & Signal Company, Swissvale, Pa., a corporation of Pennsylvania

Application April 15, 1942, Serial No. 439,002

13 Claims. (Cl. 246—8)

My invention relates to apparatus for railway train communication systems, and more specifically to apparatus to facilitate the transmission of communication current of a railway train communication system.

There are railway train communication systems which utilize the track rails as part of a transmitting circuit, the receiving apparatus of a station located on a train being effectively energized due to such communication current flowing in the rails and the transmitting apparatus of such train carried station being effective to supply such current to the rails. The low ballast resistance and the relatively high rail impedance cause a high attenuation for such current, with the result that a relatively high energy level output of the transmitting apparatus and high amplification by the receiving apparatus are required if reliable communication is to be assured between stations separated a distance of the order of a few miles.

An object of my present invention is the provision of novel and improved means to facilitate the transmission of communication current along a railway.

Another object of my invention is the provision of novel repeater facilities wherewith transmission of communication current over relatively long distances along a railway can be accomplished.

Another object of my invention is the provision of improved means for coupling a line wire with the rails of one or more tracks of a railway to facilitate the transmission of communication current to and from trains moving on such tracks.

Other objects and advantages of my invention will be apparent as the specification progresses.

In practicing my invention I provide a line circuit which includes one or more line wires extending along a railway and repeater equipment at each of one or more preselected locations. Each repeater equipment is connected to the line wires to repeat in the line wires in amplified form the communication current supplied to the line wires at some point so far distant from the repeater station that the current has become attenuated to a relatively low value. I also provide circuit connections at various points preselected with respect to the locations of the repeater equipments and each of which circuit connections is interposed between the line wires and the rails of each of the tracks of the railway for transfer of such communication current

between the line wires and the track rails so that effective and reliable communication with trains can be accomplished due to the amplification of the current by the repeater equipment.

5 I shall describe three forms of apparatus embodying my invention, and shall then point out the novel features thereof in claims.

In the accompanying drawings, Fig. 1 is a diagrammatic view showing one form of apparatus 10 embodying my invention when used with a pair of line wires for transmission of communication current along a multiple track railway. Fig. 2 is a diagrammatic view showing another form of apparatus embodying my invention 15 when used with a single line wire extending along a railway track. Fig. 3 is a diagrammatic view showing a third form of apparatus embodying my invention when used for transmission of communication current from an office to 20 any train of a division of an associated railway.

In each of the different views like reference characters are used to designate similar parts.

Referring to Fig. 1, the tracks 1, 2, 3 and 4 represent four tracks of a multiple track railway, tracks 1 and 2 being those normally used for westbound traffic, and tracks 3 and 4 being those normally used for eastbound traffic. The track rails of each of these tracks would preferably be bonded in the usual manner to insure 30 their conductivity. Each track may be formed into track sections for signaling purposes, but such use of the track rails is independent of their use for transmission of communication current. Tracks 1 and 4 are shown 35 as occupied by trains V1 and V2, respectively, and each of which trains is equipped with communication apparatus including transmitting apparatus TA and receiving apparatus RA, a microphone M1 being connected to the input

40 of apparatus TA and a loud speaker LS being connected to the output of apparatus RA. The communication apparatus would be preferably the same for each train and the transmitting apparatus TA and the receiving apparatus RA 45 are shown conventionally for the sake of simplicity since their specific construction forms no part of my present invention and it may be any one of several well-known constructions. For example, such communication apparatus 50 may be of the construction covered by Letters Patent of the United States No. 2,064,639, granted December 15, 1936, to L. D. Whitelock et al., for Communicating system. An office indicated at OF is provided with communication apparatus comprising transmitting apparatus

TA and receiving apparatus RA, which would preferably be of a construction the same as that on trains V1 and V2.

Two line wires L1 and L2 extend along the railway. These line wires may be, for example, open wires placed on a pole line along the right of way. Wires L1 and L2 are preferably transposed in the usual manner at preselected locations, one such transposition being shown at the right-hand portion of Fig. 1. The office communication apparatus is connected to the line wires through a transformer T12 having a winding 55 connected across line wires L1 and L2, and a second winding 57 connected to the input terminals of receiving apparatus RA, while the output terminals of the office transmitting apparatus TA are connected between a mid terminal of winding 55 and a ground electrode 56. It is clear that current from the office transmitting apparatus TA is applied to the line wires L1 and L2 in multiple, the line wires in multiple serving as one side of a line circuit and the ground path serving as the other side of such circuit. However, current is received by the office receiving apparatus RA from the line wires L1 and L2 in series.

The dash and dot rectangle WA indicates a wayside station at which repeater equipment is provided. This repeater equipment comprises an amplifying tube VT1 and two transformers T1 and T2. Tube VT1 is provided with a grid circuit including a winding 5 of transformer T2 and a biasing battery 6, and with a plate circuit including winding 7 of transformer T1 and a source of current, such as a battery 8. A winding 9 of transformer T1 is connected across line wires L1 and L2, while a mid terminal of winding 9 is connected to a ground electrode 10 through a winding 11 of transformer T2. A portion of current flowing in the two line wires L1 and L2 in multiple, as indicated by solid line arrows, flows to ground through the two portions of winding 9 of transformer T1 to its mid terminal and thence through winding 11 of transformer T2 to ground electrode 10. Such current induces in winding 5 of transformer T2, a corresponding electromotive force which is applied to the grid of tube VT1 to be amplified in the plate circuit of the tube causing thereby a corresponding electromotive force to appear across the outside terminals of winding 9 of transformer T1 with the result that such repeated current flows in the line wires L1 and L2 in series as indicated by the dotted line arrows. In other words, current supplied to line wires L1 and L2 in multiple, as for example by the transmitting apparatus of office OF, is amplified and reapplied to the line wires L1 and L2 by the repeater equipment, the reapplied current flowing in the line wires in series.

As shown in Fig. 1, the repeater station WA is also provided with transmitting apparatus TA and receiving apparatus RA for communication from that station. Apparatus TA and apparatus RA of station WA would preferably be similar in construction to that provided for trains V1 and V2. The output terminals of apparatus TA of station WA are connected to a winding 13 of transformer T2, and the input terminals of apparatus RA are connected to a winding 12 of transformer T1. Current supplied by the transmitting apparatus TA of station WA induces in winding 5 of transformer T2 a corresponding electromotive force which is amplified by tube VT1 and applied by transformer T1 to line wires L1 and L2 in series. Communication current sup-

plied to line wires L1 and L2 in multiple to be amplified and repeated by the tube VT1 would also induce in winding 12 of transformer T1 a corresponding electromotive force which is applied to the receiving apparatus RA. It is to be observed at this point that suitable switching means, such as that fully set forth in the aforementioned Patent No. 2,064,639, would preferably be associated with each transmitting or receiving apparatus for selectively rendering only one apparatus active at a time. It is apparent, of course, that the transmitting and receiving apparatus of repeater station WA may be omitted if desired, using only the repeater equipment.

Circuit connections between line wires L1 and L2 and the rails of the different tracks are provided at various preselected points along the railway, two such connections being shown at points P1 and P2, one on each side of the repeater station WA. These circuit connections are preferably all alike, and a description of that at point P1 will suffice for an understanding of all. A transformer T3 has a primary winding 14 connected across line wires L1 and L2, while a mid terminal of winding 14 is connected to a ground electrode 15, over a path including two asymmetric units 16 and 17 in multiple, and disposed reverse to each other, and windings 18 and 19 in multiple of two transformers T4 and T5, respectively. Two resistors 21 and 22 are connected across the rails of tracks 1 and 2, respectively, and a winding 20 of transformer T4 is connected between the mid terminals of resistors 21 and 22, while a mid terminal of winding 20 is connected to ground electrode 15 through a winding 23 of transformer T3. Similarly, two resistors 24 and 25 are connected across the rails of tracks 3 and 4, respectively, and a winding 26 of transformer T5 is connected between the mid terminals of resistors 24 and 25, while a mid terminal of winding 26 is connected to ground electrode 15 through a winding 27 of transformer T3.

In describing the operation of the apparatus of Fig. 1, I shall first assume that communication is desired between the two trains V1 and V2, and that at the start current is transmitted from train V1 to train V2. Furthermore, I shall assume that train V1 is relatively near the point P1 and train V2 is relatively near the point P2. Current from transmitting apparatus TA on train V1 is applied to the track rails of track 1 through the wheels and axles 28 and 29 of train V1, and current flows in the rails in multiple to each side of train V1 and through the rail-to-ground path in the well-known manner. Some of the current flowing in the rails to the west of train V1 flows through resistor 21, winding 20 of transformer T4, and resistor 22 to the rails of track 2, and thence through the rail-to-ground path of tracks 2 and 1 back to the point at which the current was first applied to the rails of track 1. Current flowing in winding 20 of transformer T4 creates a corresponding electromotive force across winding 18 of that transformer and current is transferred to the line wires through the circuit connection at point P1. Such current flows at a given instant say, from the lower terminal of winding 18 over asymmetric units 16 and 17 in multiple, the two portions of winding 14 of transformer T3 to its mid terminal, line wires L1 and L2 in multiple, the two portions of winding 9 of transformer T1 at station WA, winding 11 of transformer T2, ground electrodes 10 and 15 and to the top terminal of winding 18 of transformer T4. That portion of the current flowing through

winding 11 of transformer T2 of the repeater equipment is amplified and reapplied to the line wires L1 and L2 in series in the manner explained hereinbefore, with substantially one-half of such current flowing to the west and one-half to the east of station WA. At point P2, a part of the current flowing in line wires L1 and L2 in series flows in winding 39 of transformer T6 to transfer energy to winding 31 of that transformer and cause current to flow from winding 31 over a path including ground electrode 32, a rail-to-ground path for each of the tracks 3 and 4, resistors 33 and 34 connected across the rails of tracks 3 and 4, respectively, winding 35 of transformer T7 to a mid terminal and thence back to winding 31 of transformer T6. That portion of the current flowing in the rails of track T4 is available to excite a receiving coil 36 mounted on train V2 in inductive relation to the rails and connected to the receiving apparatus RA of train V2. Transmission of current from train V2 to train V1 is effected in a manner similar to that just described for transmission from train V1 to train V2, and the description need not be repeated. It is apparent from the foregoing description that communication current would be transmitted between two trains spaced apart on any one of the tracks, or between trains on any two of the tracks of Fig. 1 in substantially the same manner as described for transmission of current between trains V1 and V2.

In communication from office OF to a train, such as train V2, current applied at the office to the line wires L1 and L2 in multiple is repeated and amplified at station WA to flow in the line wires L1 and L2 in series, and a portion of such reapplied current is transferred to the rails of track 4 through the circuit connection at point P2 in the manner explained hereinbefore to excite the receiving apparatus of train V2. Current supplied to the rails of track 4 by train V2 is transferred to line wires L1 and L2 in multiple in a manner similar to that explained in connection with the current supplied to the rails at train V1, and the current supplied to line wires L1 and L2 in multiple from track T4 is repeated and amplified at station WA to cause current to flow in line wires L1 and L2 in series, which re-applied current is available to excite the receiving apparatus at office OF through winding 57 of transformer T12.

Communication between station WA and either train V1 or V2 is effected over line wires L1 and L2 and the connections at points P1 and P2. Current from the transmitting apparatus TA of station WA is applied through winding 13 of transformer T2 to the amplifier tube VT1 and thence to the line wires in the manner explained hereinbefore. Such current flows in the line wires L1 and L2 in series and is transferred at points P1 and P2 to the rails of the different tracks for exciting receiving apparatus of a train moving on any one of the tracks. Also current supplied to a track, for example, by train V2 to track 4, is transferred through the connection at point P2 to the line wires L1 and L2 in multiple, and is applied to the equipment at station WA to induce in winding 12 of transformer T4 a corresponding electromotive force which is available to excite the receiving apparatus RA of station WA.

The asymmetric units, such as units 16 and 17, included in each circuit connection between the line wires and the track rails are preferably of the dry surface type such as copper oxide recti-

fier elements which are characterized by a relatively low impedance for a current of large value and a high impedance for current of low value. These units are inserted in the circuit connection to offer a relatively low impedance to current of relatively large value and a relatively high impedance to current of a relatively low value. Current is thus transferred to the line wires at a connection in the vicinity of a train with little attenuation because the communication current flowing in the rails is of relatively large value and the units offer low impedance. At some distance away from the train the line current becomes weaker and the asymmetric units offer a higher impedance, and thereby prevent the energy from being wasted by feeding back into the track rails at these distant points. Such asymmetric units only serve as an aid and may not be required.

Since the attenuation of the communication current is small in the line wires L1 and L2 in multiple, and since the power required to energize each repeater station amplifier is small, the original energy applied to the line wires L1 and L2 may be amplified and distributed at several different repeater stations, and thus transmission effected over a relatively long distance along the railway. Also, since the direction of the flow of current in the rails is reversed at adjacent circuit connections due to the transposition of the line wires, there is little danger of the rail current feeding back into the line wires and setting up excessive regeneration.

Referring to Fig. 2, a line wire L3 extends along a railway of which only track 1 is shown, and on which track 1 a train V3 provided with communication apparatus is moving. Line wire L3 is included in a line circuit formed by line wire L3 as one side and the ground path as the other side. Office OF of Fig. 2 is provided with communication apparatus connected to line circuit through a transformer T15, whose winding 70 is connected between line wire L3 and a ground electrode 71 while the output terminals of transmitting apparatus TA are connected to a winding 72 of transformer T15, and the input terminals of receiving apparatus RA are connected to a winding 73 of transformer T15. A wayside station WA is provided with repeater equipment comprising an amplifier tube VT1 and transformers T8 and T9. Tube VT1 of Fig. 2 is provided with a grid circuit including winding 37 of transformer T8 and a biasing battery 38, and with a plate circuit including a winding 39 of transformer T9 and a suitable source of current. Winding 40 of transformer T8, a condenser 84 and a resistor 41 are interposed in a connection between line wire L3 and a ground electrode 42, while winding 43 of transformer T9 is included in a circuit between a mid terminal of winding 40 and the terminal of resistor 41 adjacent ground electrode 42. A portion of communication current flowing along line wire L3 flows to ground at station WA through the line-to-ground connection, and an electromotive force is induced in winding 37 of transformer T8 to be applied to tube VT1 to cause an amplified current to appear in the plate circuit, and which plate current is fed to the mid terminal of winding 40 of transformer T8 to create a voltage across the lower portion of winding 40 and resistor 41. This voltage caused by the amplified current causes current to flow in the line circuit and which current reinforces the original communication current flowing in the line circuit. At points toward the source of the

original current, the amplified current might tend to cancel the original current. However, the amplified current must be exactly 180 degrees out of phase for cancellation of the original current, and such phase relation will rarely, if ever, occur because of the inductance of the various circuits. The largest advantage for points beyond the repeater station occurs when the amplified current and the original current are in phase, but this condition will be rare. However, the amplified current is much stronger than the original current, and the resultant would be a current much larger than the original. Such repeater equipment can be spaced apart as required along the railway for propagation of the communication current over relatively long distances.

Circuit connections are provided between line wire L3 and the rails of track 1 at various points, and of which circuit connections those at two points P3 and P4 only are shown in Fig. 2 since these are sufficient to fully illustrate the invention. These circuit connections are preferably all alike, and looking at the circuit connection at point P3, a transformer T10 has one winding 44 connected between line wire L3 and a ground electrode 45 while its other winding 46 is connected between a ground electrode 48 and a mid terminal of a resistor 47 connected across the rails of track 1.

Assuming current is supplied to the rails from the transmitting apparatus TA of train V3 to flow in the rails and the rail-to-ground path, a portion of such current flows between the rails and ground through resistor 47 and winding 46 of transformer T10 at point P3, and a portion flows between the rails and ground through winding 49 of transformer T11 at point P4. The connections of transformers T10 and T11 are such that the relative polarities of the energy transferred to winding 44 of transformer T10 and to winding 50 of transformer T11 cause currents to flow in line wire L3 which pass through the line-to-ground connection at the repeater station WA in the same direction. The resultant current, after amplification by the repeater equipment, is fed back to line wire L3 to reinforce the original current in the manner explained hereinbefore. At office OF a portion of such current flows from line wire L3 to ground through winding 70 of transformer T15 to excite the receiving apparatus RA through winding 73 of transformer T15. Transmission of current from the transmitting apparatus of office OF to the receiving apparatus of train V3 is accomplished in a similar manner and the description need not be repeated.

In Fig. 3 there is shown apparatus to facilitate the transmission of communication current between an office and a train at any point of a railway division, which division may be of 100 miles or more in length. Line wires L1 and L2 are shown as extending from office OF along the division of the railway, of which the two tracks 1 and 2 are shown. The office OF of Fig. 3 is provided with communication apparatus similar to that at the office OF of Fig. 1.

At some point distant from office OF, such as for example, the central point of the railway division, a repeater station WB is located. The repeater equipment of station WB comprises an amplifying tube VT2 and transformers T13 and T14, together with a winding 58. Winding 58 is connected across line wires L1 and L2, while its mid terminal is connected to ground electrode 59 through a winding 60 of transformer T13 and a resistor 61. Hence a portion of communication

current supplied to line wires L1 and L2 in multiple at the office OF flows to ground through winding 60 of transformer T13 to transfer energy to winding 62 of transformer T13, and which energy is applied to the grid of tube VT2 to be amplified in the plate circuit of that tube, the plate circuit including a winding 82 of transformer T14. Such plate circuit current flowing in winding 82 causes energy to be transferred to winding 63 of transformer T14 and applied to the mid terminal of winding 60 of transformer T13 so that a portion of the amplified current is reapplied to the line wires L1 and L2 in multiple to reinforce the original current flowing in the line wires. That is, the current supplied at the office OF to line circuit including wires L1 and L2 in multiple, is amplified by the equipment of station WB and reapplied to the same line circuit to flow in the line wires L1 and L2 in multiple. If required, other repeater stations similar to that of station WB may be provided along the railway division, but since the attenuation of the current in the line wires would be relatively small, one such repeater station for a division may be all that would be required.

Repeater equipment is also provided at each of a plurality of other locations to repeat and amplify the current flowing in the circuit including line wires L1 and L2 in multiple and cause current to flow in the circuit including line wires in series for transfer to the rails of the various tracks. Two such repeater stations WA1 and WA2 are shown in Fig. 2, one station on each side of the repeater station WB. Each repeater station WA1 and WA2 is provided with repeater equipment of the same construction as that of station WA of Fig. 1, except that an indirect heater type of amplifying tube is used, and a condenser-resistor biasing unit replaces the biasing battery 6 of the equipment of Fig. 1.

Circuit connections between the line wires L1 and L2 and the rails of tracks 1 and 2 of Fig. 3 are provided at various points along the division, and of which points only four points P5, P6, P7 and P8 are shown. These circuit connections of Fig. 3 are substantially the same as shown in Fig. 1 for tracks 1 and 2 except the asymmetric units are omitted and the rails of track 2 are used as a ground electrode. In Fig. 3, a train V4 provided with communication apparatus is shown as occupying track 1 in the vicinity of the repeater station WA2.

In communication between office OF and train V4, current is supplied to line wires L1 and L2 in multiple at the office and this current flowing in the line wires in multiple, is repeated at station WB and then that portion of the repeated current supplied to the line wires is again repeated by the equipment of station WA2 to cause current to flow in the line wires in series. This latter current is transferred to the rails of track 1 through the circuit connections at points P7 and P8 and is available to excite the receiving apparatus of the train V4. Current applied to the rails of track 1 by train V4 is transferred to the line wires L1 and L2 through the circuit connections at points P7 and P8 to flow in the line wires in multiple, and such current is repeated at station WB to reinforce the original current flowing in the line wires in multiple. At a repeater station near the office, such as station WA1, the current is amplified and reapplied to the line wires to flow in the line wires in series, and such current flowing in the winding 55 of transformer T12 at the office induces a cur-

rent in winding 57 which is available to excite the receiving apparatus RA of the office.

Although I have herein shown and described but three forms of apparatus for railway train communication systems embodying my invention, it is understood that various changes and modifications may be made therein within the scope of the appended claims without departing from the spirit and scope of my invention.

Having thus described my invention, what I claim is:

1. In apparatus for a railway train communication system, the combination comprising, circuit means including a line wire extending along a railway for transmitting communication current to different points along the railway, a first station provided with transmitting apparatus coupled to said circuit means to cause communication current to flow in the line wire, repeater equipment including an electron tube amplifier at a preselected location along the railway and connected to said circuit means to repeat in the circuit means such communication current in amplified form, and train carried receiving apparatus mounted on a train moving on a track of said railway and coupled to said circuit means to be effectively energized by the communication current flowing in said circuit means due to the amplification effected by said repeater equipment.

2. In apparatus for a railway train communication system, the combination comprising, a line wire extending along a railway, a station provided with transmitting apparatus coupled to said line wire to cause communication current to flow in the line wire, repeater equipment including an electron tube amplifier placed at a preselected location along the railway and having connection to said line wire to receive said communication current and cause such current in amplified form to flow in the line wire, a circuit connection to connect said line wire to the rails of a track of said railway at a location preselected with respect to the location of said repeater equipment, and train carried receiving apparatus including a circuit coupled to the rails and effectively energized by the communication current transferred to the rails through said circuit connection due to the amplification effected by said repeater equipment when the train occupies said track in the vicinity of said circuit connection.

3. In apparatus for a communication system, the combination comprising, a first circuit including two conductors in multiple as one side of the circuit and another conducting path as the other side of the circuit, transmitting apparatus connected across the two sides of said first circuit to cause communication current to flow therein, repeater equipment including an electron tube amplifier having input terminals connected across the two sides of first circuit and output terminals connected across said two conductors to repeat in amplified form the communication current flowing in said first circuit in another circuit including said two conductors in series, and receiving apparatus coupled to said other circuit effectively energized by the communication current thus caused to flow in said other circuit.

4. In apparatus for a communication system, the combination comprising, a first circuit including two conductors in multiple as one side of the circuit and another conducting path as the other side of the circuit, transmitting appa-

ratus connected across the two sides of said first circuit to cause communication current to flow therein, an electron amplifier tube having a plate, a cathode and a grid; a first winding connected across said two conductors, a second winding coupled to said first winding and included in a plate circuit connected to the plate and cathode of said tube, a third winding interposed between a mid terminal of said first winding and said other conducting path of said first circuit, a fourth winding coupled to said third winding and connected across the grid and cathode of said tube to cause the amplifying of the communication current flowing in said first circuit and the supplying of such amplified current to a second circuit including said two conductors in series, and receiving apparatus coupled across said two conductors effectively energized by the communication current thus caused to flow in said second circuit.

5. In apparatus for a railway train communication system, the combination comprising, two line wires extending along a railway, a station provided with transmitting apparatus having one terminal connected to said two line wires in multiple and another terminal connected to ground to cause communication current to flow in the two line wires in multiple, repeater equipment at a preselected location along said railway and having its input side connected between the two line wires in multiple and ground and its output side connected across said two line wires to receive said communication current from the two line wires in multiple and reapply such current to the two line wires in series, a circuit connection at a point preselected with respect to said repeater equipment location connected across the two line wires and to the two rails of a track of said railway to transfer such current flowing in the line wires in series to the rails of said track, and train carried receiving apparatus including a circuit coupled to the rails effectively energized by such current thus transferred to the rails when the train occupies said track in the vicinity of said circuit connection.

6. In a railway train communication system, the combination comprising, a line wire extending along a railway, a station provided with transmitting means connected between said line wire and ground to cause communication current to flow in said line wire, repeater means including an electron tube and a first and a second transformer located at a preselected location along the railway, said first transformer having a first winding connected between said line wire and ground and a second winding interposed in a grid circuit of said tube and said second transformer having a first winding interposed in a plate circuit of said tube and a second winding connected between a mid terminal of said first winding of the first transformer and ground to reinforce the original communication current flowing in said line wire by such current amplified by said tube, a circuit connection including transformer means connected between said line wire and the rails of a track of said railway to transfer such current from said line wire to the rails of said track, and train carried receiving means including a circuit coupled to the rails and effectively energized by the current thus transferred to the rails when the train occupies said track.

7. In a railway train communication system, the combination comprising, a pair of line wires extending along a multiple track railway, re-

peater equipment including an electron tube and a first and a second transformer at a preselected location along said railway, said first transformer having a first winding connected across said line wires and a second winding interposed in a plate circuit of said tube and said second transformer having a first winding connected between a mid terminal of the first winding of the first transformer and ground and a second winding interposed in a grid circuit of said tube to repeat communication current flowing in a circuit including the line wires in multiple in another circuit including the line wire in series, two circuit connections one at each of two points on opposite sides of said repeater location, each said circuit connection including transformer means having connections to the rails of each track of said railway and to said line wires for transferring communication current from the rails of any track to the circuit including the line wires in multiple and from the circuit including the line wires in series to the rails of each of said tracks, a first train moving on one track of the railway and provided with transmitting apparatus effective to supply such communication current to the rails, and a second train moving on another track of the railway and provided with receiving apparatus coupled to the rails and effectively energized by the current supplied by said first train transmitting apparatus due to said circuit connections and said repeater equipment.

8. In a railway train communication system, the combination comprising, a pair of line wires extending along a multiple track railway, repeater means including an electron tube amplifier at a preselected location along the railway, means to couple the input side of said amplifier to a connection between said line wires in multiple and ground and to couple the output side of said amplifier across said line wires, two circuit connections one at each of two points on opposite sides of said repeater location; each said circuit connection including transformer means having connection to said line wires, to ground and to the rails of each track of said railway for transfer of communication current between the line wires and the rails of each track of the railway; and two train carried stations spaced apart along said railway and each station provided with transmitting apparatus effective to supply communication current to the rails and receiving apparatus energized by such current flowing in the rails for communication between said two stations due to said circuit connections, said line wires and said repeater means.

9. In a railway train communication system, the combination comprising, two train carried stations spaced apart along a railway and each provided with transmitting apparatus coupled to the rails of a track of the railway to supply communication current thereto and receiving apparatus coupled to the rails to receive such current therefrom, a line wire extending along said railway, a circuit connection at each of a plurality of preselected points along the railway and each including transformer means having connection to the rails of each track of the railway and to said line wire for transfer of such communication current from the rails to the line wire or from the line wire to the rails, and repeater means including an electron tube amplifier connected to said line wire to repeat in amplified form such communication current

flowing in said line wire to aid communication between said two stations.

10. In a railway train communication system, the combination comprising, two train carried stations spaced along a first and a second track of a multiple track railway and each provided with communication apparatus coupled to the rails to supply communication current thereto and to receive such current therefrom, a pair of line wires extending along the railway, a circuit connection at each of a plurality of preselected points along the railway and each of which connections includes a first and a second transformer, a first winding of said first transformer connected across said line wires while a first winding of said second transformer is connected between the rails in multiple of the first track and the rails in multiple of the second track and the second winding of the first transformer is connected between ground and a mid terminal of the first winding of the second transformer and the second winding of the second transformer is connected between ground and a mid terminal of the first winding of the first transformer whereby current is transferred from the line wires in series to the rails in multiple of each track and from the rails in multiple of either track to the line wires in multiple, and repeater means including an electron tube amplifier connected to said line wires to receive current from the line wires in multiple and to reapply the current in amplified form to the line wires in series to aid in communication between said two stations.
11. In a railway train communication system, the combination comprising, a pair of line wires extending along a railway, an office provided with communication apparatus effective to supply communication current to a first circuit including said line wires in multiple and ground and to receive such current from a second circuit including said line wires in series, a first repeater station including an electron tube amplifier connected between said line wires and ground to repeat in amplified form the current flowing in said first circuit, a second repeater station including an electron tube amplifier having its input connected between the line wires in multiple and ground and its output connected across said line wires to repeat in amplified form the current flowing in said first circuit in said second circuit, a circuit connection including transformer means connected between said line wires and to the rails of a track of said railway for transfer of such communication current, and a train carried station provided with communication apparatus coupled to the rails to supply such current thereto and to receive such current therefrom for communication with said office through the medium of said circuit connection and said first and second circuits.

12. In a railway train communication system, the combination comprising, a pair of line wires extending along a railway, an office provided with communication apparatus effective to supply communication current to a first circuit including said line wires in multiple and ground and to receive such current from a second circuit including said line wires in series, a first repeater station at a preselected location along the railway and including an electron tube amplifier having both its input and output sides coupled to said first circuit to reinforce the communication current flowing in said first circuit at said preselected location, a second repeater station

located at another preselected location along the railway and including an electron tube amplifier having its input side coupled to said first circuit and its output side coupled to said second circuit to repeat in said second circuit the current flowing in said first circuit, a plurality of circuit connections one at each of a plurality of preselected points along the railway and each such circuit connection including transformer means coupled to the rails of a track of the railway and to each of said first and second circuits to transfer current between said rails and said circuits; and a train moving on said track provided with communication apparatus capable of supplying such communication current to the rails and to receive such current from the rails for two-way communication with said office by the medium of said circuit connections, said repeater stations and said first and second circuits.

13. In a railway train communication system, the combination comprising, a pair of line wires extending along a railway, a line circuit including said pair of line wires in multiple as one side

- 5 of the circuit and the ground path as the other side of the circuit, transmitting apparatus at a first location along the railway and coupled to said line circuit to supply a communication current thereto, a repeater station at a preselected location along the railway and including an electron amplifier tube and a first and a second transformer, said first transformer having a first winding interposed between said line wires in
10 multiple and ground and a second winding interposed in a grid circuit of said tube and said second transformer having a first winding interposed in a plate circuit of said tube and a second winding interposed between a mid terminal
15 of the first winding of the first transformer and ground to repeat in amplified form in said line circuit at said preselected location the communication current supplied to the line circuit at said first location, and receiving apparatus coupled to the line circuit effectively energized by the communication current due to the amplifying of the current at said repeater station.
